(57) **CLAIM**

The ornamental design for a pillow responsive to head movement to reduce snoring, as shown and described.

DESCRIPTION

FIG. 1 is a perspective view of a pillow responsive to head movement to reduce snoring with the broken-line disclosure of a bed for illustrative purpose only and forming no part of the claimed design;

FIG. 2 is an end elevational view with the opposite end being a mirror image;

FIG. 3 is a front elevational view;

FIG. 4 is a plan view;

FIG. 5 is a rear elevational view; and,

FIG. 6 is a bottom plan view.
